MARTIN FEYBUSCH, OF NEW YORK, N. Y.

LABEL-FEEDING DEVICE.

1,180,708.

Specification of Letters Patent. Patented Apr. 25, 1916.

Application filed May 27, 1915. Serial No. 30,815.

To all whom it may concern:

Be it known that I, MARTIN FEYBUSCH, a subject of the Emperor of Germany, and a resident of New York city, in the county and State of New York, have invented certain new and useful Improvements in Label-Feeding Devices, of which the following is a specification.

This invention relates to a device by means of which labels or similar articles may be withdrawn from a magazine and conveyed to a gumming or other machine for subsequent treatment in a simple, and reliable manner.

In the accompanying drawing: Figure 1 is a plan of a label feeding device embodying my invention; Fig. 2 an end elevation thereof; Fig. 3 a section on line 3—3 Fig. 1; Fig. 4 a detail of the glue pot; Fig. 5 a detail of the clutch mechanism, and Fig. 6 a detail of the plunger.

The device comprises essentially a frame 1, to which is attached, by screw 2, a platform 3, provided with a centrally disposed slot 4. Upon platform 3 is mounted a label magazine formed of a side plate 5, and a pair of end plates 6. The latter are by screws 7, secured to brackets 8, from which extend laterally, rods 9 that engage apertured posts 10, to which the rods are clamped by screws 11. By slackening these screws, brackets 8, together with end plates 6, may be moved farther inward or outward so that in this way the size of the magazine may be adjusted. The magazine is open at its bottom, and is centered over slot 4, the labels 12 being supported by a plurality of lugs 13 projecting inwardly from plates 5 and 6 and located in a plane above the surface of the platform.

Beneath platform 3, there is journaled in frame 1, a pair of rollers 14, 15 over which passes an endless conveyer belt 16, composed of rubber or other flexible material, the upper run of said belt being accommodated within slot 4.

Means are provided for applying an adhesive to the belt, means for deflecting the upper gummed run of the belt into engagement with the lowermost label, and means for advancing the belt together with the label adhering thereto, to the gumming or other machine for further treatment. As shown, a glue pot 17 is mounted on frame 1 beneath the lower run of belt 16, and into

this pot dips a transfer roller 18 which contacts with such lower run and is thus adapted to apply the adhesive thereto. Roller 18 is rotated as follows: The power shaft 19 driven by belt 20, drives by pulley 21, belt 22, and pulley 23 a stub shaft 24, which is intergeared at 25 with the shaft 26 of roller 18. Shaft 26 is engaged by a scraper 27, depending from a slotted cover 28, such cover constituting a scraper for roller 18. Cover 28 together with scraper 27 may be adjusted by a set screw 29, and may be clamped in position by nuts 30.

It is preferred to pivotally mount glue pot 17 upon a shaft 31, so that by tilting the pot, the depth to which the transfer roller 18 enters the liquid adhesive is regulable. The means for tilting the pot comprise a fixed screw stem 32, that is engaged by a threaded head 33, carrying a pair of disks 34 which straddle a pin 35 carried by the glue pot. Head 33 may be provided with spanner holes and by turning it, the pot may be tilted either upward or downward on shaft 31. When the belt is advanced in an intermittent manner, as hereinafter described, its gummed lower run will in time form its upper run, which is thus coated with the adhesive on its upper face and directly beneath the label magazine. This upper run is engaged by a plunger 36, that is located directly beneath the same, and extends sidewise from a plunger rod 37, the shaft 38 of which is guided in a bearing 39, and is influenced by a spring 40. Plunger 36 is actuated from shaft 19 as follows: Shaft 19 is by wheels 41, 42 intergeared with a shaft 43 carrying a cam 44 which is engaged by a roller 45 on an arm 46. This arm is connected to a rock shaft 47 having an arm 48 that enters a notch of rod 37, so that by the rotation of cam 44, the plunger will be alternately raised and lowered. As the plunger is raised, it will be projected upwardly through slot 4 of table 3, and will accordingly expand the upper run of belt 16. This run is thus lifted by the plunger through slot 4, so as to rise into the plane of the supports 13 within the label magazine and come into contact with the lowermost label 12 to which it becomes attached. Inasmuch as the magazine and the labels contained therein, extend a distance sidewise beyond the slot, the belt will not underlie the entire bottom of label 12, but will con-

95

110

- tact with the same only along its central line, the right and left portions of the label remaining free, so that an unduly firm adherence of the label to the belt is prevented.
- 5 When now the plunger is lowered, the belt, owing to its elastic properties, is free to resume its normal position, in which the upper surface of the belt will be flush substantially with the surface of the table. In this way, 10 the label after being drawn off lugs 13, will become supported upon the table, along which it will be caused to advance by the further motion of the belt. This further motion consists in an intermittent advance 15 by means of which the label is carried to its place of destination. The means for imparting an intermittent forward movement to the belt are as follows: Upon shaft 43 is mounted a second cam 49 engaged by a 20 roller 50 journaled to one end of a slotted rod 51, which is engaged by a guide pin 52. The other end of rod 51 is pivoted at 53 to the oscillative shank of a toothed segment 54, turning on center 55. Segment 54 25 engages a pinion 56 fast on the hub of a clutch box 57 that is loosely mounted on the shaft 58 of roller 14. To clutch box 57 are pivoted pawls 59 adapted to engage a ratchet wheel 60 fast on shaft 58. The correlation of the parts is such that when segment 54 is swung forward or to the right, 30 it will by the mechanism described, rotate roller 14, so as to correspondingly advance belt 16, while during the return movement 35 of the segment, no motion is transmitted to the roller. In this way the desired intermittent forward movement will be imparted to belt 16, whereby the label 12 riding thereon, will be carried from beneath the magazine toward the delivery end of the device. 40 Here there are provided a pair of stripper plates 61 that flank slot 4, and project into close proximity to belt 16, so as to peel the label off the same. Strippers 61 extend a 45 distance beyond roller 15 and conduct the forward end of the partly stripped label toward and between a pair of conveyer shafts by means of which the label is carried to the gumming machine to be operated upon. 50 As shown, power shaft 19 assumes the function of one of the conveyer shafts, while the other shaft 62 is mounted in close proximity thereto and is provided with milled gripping sections 63.
- 55 The operation of the device will be apparent from the foregoing description. The belt after being coated with adhesive is, while at rest, raised by the plunger into contact with the label. Upon the recession 60 of the plunger, the belt with the label adhering thereto, resumes its normal position, and is then advanced, by the toothed segment, to carry the label toward the strippers. Here the label is peeled off the belt 65 and is by the conveyer shafts, carried to

the gumming machine. It will be seen that by the construction described, all grippers and their actuating devices are entirely dispensed with, the belt assuming the dual function of withdrawing the label from the 70 magazine and of feeding it away from the magazine after its withdrawal. In this way the construction of the device is greatly simplified while a positive and reliable action is insured.

75

I claim:

1. A label feeding device comprising means for supporting a label, an endless flexible belt, means for applying an adhesive to the lower run of said belt, means for deflecting the upper run of the belt into contact with the label, and means for imparting an intermittent movement to the belt.

80

2. A label feeding device comprising a 85 frame, a slotted platform carried thereby, a label magazine mounted on the platform, a pair of rollers, an endless flexible belt engaging said rollers, means for imparting motion to one of said rollers, means for applying an adhesive to the lower run of the belt, and a vertically movable plunger engaging the belt and adapted to deflect one of its runs through the platform-slot into the magazine.

90

3. A label feeding device comprising a frame, a slotted platform carried thereby, a label magazine mounted on the platform a pair of rollers, an endless flexible belt engaging said rollers, means for imparting 100 motion to one of said rollers, means for applying an adhesive to the lower run of the belt, a vertically movable plunger engaging the belt and adapted to deflect one of its runs through the platform-slot into the 105 magazine, and a stripper engaging said run.

95

4. A label feeding device comprising a frame, a slotted platform carried thereby, a label magazine mounted on the platform, a pair of rollers, an endless flexible belt engaging said rollers, an oscillative rack, a clutch operable thereby, means operable by the clutch for imparting intermittent rotary motion to one of said rollers, means for applying an adhesive to the belt, and a 110 vertically movable plunger engaging the belt.

110

5. A label feeding device comprising a slotted platform, a label magazine mounted thereon, an endless flexible belt, a glue pot, 120 a transfer roller entering said pot and engaging the lower belt-run, a vertically reciprocable plunger engaging the upper belt-run and adapted to deflect the same into the magazine, means for imparting an intermittent forward movement to the belt, a pair of strippers engaging the belt and flanking the platform-slot, and means for drawing a label off the strippers.

120

6. A label feeding device comprising a 130

slotted table, means above said table for supporting a label, an endless flexible feed belt having a lower run and an upper run, adhesive-applying means engaging the 5 lower run, and means for deflecting the upper run through the table-slot into the plane of the label-supporting means.

7. A label feeding device comprising a label magazine, having raised label supporting means, a table beneath said supporting 10 means, said table having a slot that extends longitudinally through said magazine, an endless flexible feed belt, having an upper run and a lower run, means for applying an adhesive to the lower run of said belt, and a plunger engaging the upper run, 15 said plunger being adapted to lift said upper run into the plane of the label support-

ing means, and to lower said run into the plane of the table. 20

8. A label feeding machine comprising a label magazine having raised label supporting means, a table beneath said supporting means, said table having a slot that extends longitudinally through the magazine, an 25 endless flexible feed belt beneath the table and aligned with the table-slot, means for supplying intermittent forward movement to the belt, means for applying an adhesive to the lower belt run, a plunger engaging 30 the upper belt run and adapted to project the same through the table-slot, and means for actuating said plunger while the belt feeding means are inert.

MARTIN FEYBUSCH.
